CAISSON

William R. Marsden, Brooklyn, N. Y.

Application February 8, 1935, Serial No. 5,543

4 Claims. (Cl. 255—19)

This invention relates to new and useful improvements pertaining to methods of subsurface construction work, and particularly to those types used for subsurface foundations where the presence of heavy earth and hydrostatic pressures complicate the sinking of caissons to stable strata.

Various methods are employed in caisson construction. One is the open caisson method where usually a caisson form or cylinder is gradually sunk to a firm foundation by a combination of excavating the earth on the inside of the cylinder or form by machine or man power, and a forcing down of the cylinder or form by weight or other mechanical means. This type of caisson has a limited field of use.

Another is the pneumatic method where sand hogs working under air pressure, dig the earth out at the bottom of the working chamber, which with its overhead attached caisson penetrates the earth while digging proceeds. Heavy weights are usually located on top of the caisson to counteract compressed air uplift in the caisson and to overcome frictional resistance to penetration by contact of the caisson and the earth walls.

Still another is the so-called mud method, where a hole is made in the earth by a boring tool, and a mud content of artificially regulated consistency is left in the hole until final boring penetration is reached. This mud content in the unprotected hole aids in preventing excessive caving in of the earth walls of the hole during the boring process. When final penetration depth is reached, the permanent caisson form is forced through the mud, the mud is removed, the caisson form is cleaned out, and the concrete is deposited.

It is the object of my invention so to construct caissons and the like, to reduce the cost and facilitate the practicing of present caisson methods by the use of a specially designed machine.

The invention is illustrated in the accompanying drawings in which—

Fig. 1 shows a side elevation partly in cross-section of the caisson constructor, with the caisson cylinder and its cutting section in position and with power hammers bearing on top of the caisson cylinder;

Fig. 2 shows a caisson cylinder as used without a separate cutting section;

Fig. 3 shows a sectional plan view on line 1—1 of Fig. 4;

Fig. 4 shows a view of the structure illustrated in Fig. 1 taken from the front, with sectional view of the caisson cylinders; and

Fig. 5 shows as much of an arrangement like the one shown in Fig. 1 as is necessary for one

skilled in the art, and in which a movable platform bears on top of the caisson cylinder.

In these drawings, like reference numerals indicate like parts throughout the several figures.

1 is a bed frame resting on transporting parts 2 such as rollers, skids, caterpillar tractors or the like. This bed frame supports the operating power equipment (not shown) or, the power equipment can be supported on a platform 4. The front edge of the bed frame 1 supports a vertical tower on legs 5 and 6 with the necessary structural bracing and supports. This tower has a movable platform 4 with sliding guides 20 in contact with legs 5 and 6 so as to permit raising and lowering of the platform to accommodate its elevation to suitable operating conditions. The purposes of this tower are to support the necessary operating machinery; to act as a guide for boring and caisson revolving apparatus, and to rest as a weight on top of the caisson as an aid in forcing the caisson into the earth.

Speed reduction gearing is used between a source of power such as a motor (not shown), and a main gear 9 through which passes a vertical drive keyed shaft of hollow steel 3. The shaft is made up of two or more parts, so designed as to telescope one within the other for the purpose of providing a variable boring range. On the inside of this hollow shaft, a steel cable 7 is attached at the lower end of the shaft with a swivel connection. The cable runs up through the center of the shafting to sheaves 8 located on top of the tower and hence to the engine drum (not shown).

On the lower section of this shafting and intermediate its length, metal arms 10 are attached which connect with fittings 11 fastened to the inside of a revolving cylinder 12 or 15 for the purpose of transmitting circular motion to the cutting edge of the cylinder. These arms are of adjustable length so as to be adaptable to use in caisson cylinders of variable diameters.

A boring tool 13 is attached to the lower end of shafting 3 to loosen the earth inside the cylinder. The arms of this boring tool are adjustable in length so as to bore the earth over a required radius.

In accordance with my invention the caisson cylinder is revolved as a unit consisting of 15, Fig. 2, or a main cylinder 14 and an auxiliary 50 revolving and cutting cylinder 12 (Fig. 1). The cutting cylinder 12 can be of any desired length, and of a diameter to allow to the next upper section of the caisson cylinder 14 vertical play inside it. On the bottom edge of cylinder 14 55

and intermediate its length, metal rings 18 are provided. At the top edge of cutting cylinder 12 and intermediate its length metal rings 17 are provided. These rings act as a seal between 5 the two caisson cylinder sections; they prevent separation of the two sections of the cylinder one from the other, and they act as a pulling down or a driving down connection for one or the other of these sections.

10 I use a combination of methods to cause the caisson cylinders to penetrate the earth; the cylinder 15 may be rotated; the main cylinder 14 may be pulled down by the rotating cutting section 12; and compressed air hammers 16 acting 15 on top of the cylinder may be used. In the modification shown in Fig. 5, the caisson is caused to penetrate the earth by the weight of the platform 4 resting on top of cylinder 14.

In general, the operations in constructing a 20 caisson by my method are as follows: The caisson constructor being placed at caisson location, the caisson cylinder with or without a separate cutting section as conditions necessitate, is placed in position in front of the caisson constructor. 25 The boring and revolving apparatus 10 and 13 is lowered by shaft 3 to the earth inside the cylinder and the arms 10 hooked up to fittings 11 on the cylinder. Power is transmitted through the gear 9 to the drive shaft 3, hence to the cylinder 30 revolving arms 10 and the cylinder, and to the boring tool 13. The revolving cutting edge of the cylinder penetrates the earth and at the same time the boring tool 13, in conjunction with water introduced when necessary, loosens the 35 earth inside the cylinder.

Penetration may proceed throughout the length of the caisson if practical, or the penetration process may be stopped at any point in the caisson length, the boring and revolving apparatus 40 quickly raised by use of the telescoping shafts, and the loosened earth removed by any of the excavating methods in common use.

In the penetration of earth, boulders, hardpan or other obstructions may be encountered. A 45 cylinder cutting edge 19 with a cutting shape of

special cutting steel may be used, or the cutting edge may be used in combination with a shot coring method, where chilled steel shot is introduced to the revolving cutting edge of the cylinder to sever obstructions, so that the interfering portion can be removed. The cutting edge grooves a seat for the bottom edge of the caisson cylinder in the final strata. 5

When final penetration is reached, the caisson cylinder is excavated, cleaned out and filled with 10 concrete.

I believe my invention to be susceptible of embodiment and capable of practice by other means than those specifically illustrated and described, and therefore do not intend to be understood as 15 limiting it thereto, save as defined in the appended claims.

What I claim is:

1. In a machine for subsurface construction work, a cylindrical caisson having a lower cutting 20 revolving section and a contiguous upper section, a limited sliding connection between said sections, a telescoping hollow shaft for revolving the lower section, adjustable metal arms mounted on said shaft engaging the cutting section, and 25 a boring tool mounted on the lower end of said hollow shaft.

2. In a machine for subsurface construction work, a cylinder having an upper and a lower section, a coupling between said sections whereby one will cause vertical displacement of the other, a telescoping shaft projecting through said cylinder sections and rotating the lower section, and a vertically movable platform for applying 30 vertical force to the upper section. 35

3. In a machine for subsurface construction work, a cylindrical caisson, a telescoping hollow shaft for revolving said caisson, and adjustable metal arms mounted on said shaft and engaging 40 said caisson.

4. In a machine in accordance with claim 3, and a boring tool mounted on the lower end of 45 said telescoping hollow shaft.

WILLIAM R. MARSDEN. 45
